UNITED STATES PATENT OFFICE.

JOSEPH R. LE CLAIR, OF WYANDOTTE, MICHIGAN, ASSIGNOR OF ONE-HALF TO FELIX A. PERRY, OF WYANDOTTE, MICHIGAN.

WINDOW-CLEANING DEVICE.

1,270,629.

Specification of Letters Patent. Patented June 25, 1918.

Application filed March 9, 1917. Serial No. 153,706.

To all whom it may concern:

Be it known that I, JOSEPH R. LE CLAIR, a citizen of the United States, residing at Wyandotte, in the county of Wayne and State of Michigan, have invented a new and useful Window-Cleaning Device, of which the following is a specification.

This invention relates to window cleaners especially adapted for use on the window of motorman's vestibule of street and interurban cars, and it consists in the novel features of construction and operation as hereinafter set forth and claimed.

The invention has for its object to provide a simple and effective cleaning device for attachment to the frame or sash of a window, particularly to the front window of the motorman's vestibule of a street car so as to yieldably and movably bear in engagement with the inner and outer surfaces of the window pane, and which may be manually operated to slide in wiping contact across the planes of the glass in the manner of a squeegee to effect the removal of any accumulation of dust or moisture thereon and thus enable both sides of the window to be readily cleaned simultaneously.

In the accompanying drawings is illustrated a preferred structural embodiment of my invention, and in which,

Figure 1 is a view in elevation of a portion of the front end or motorman's vestibule of a street car showing the window equipped with the present invention in position thereon for operation.

Fig. 2 is a transverse vertical section through the window and upper rail of the frame embraced by the cleaning device, the body portions of which are shown in elevation engaged with opposite faces of the window pane.

Fig. 3 is a perspective view of one of the supporting brackets carrying a flexible wiping strip, the lower portion of which is broken away.

Fig. 4 is a horizontal section through the heads of the supporting brackets mounted to slide in a slot formed through the upper rail of the window frame.

Fig. 5 is a plan view of a leaf spring for applying tension to yieldably retain the bracket heads slidably engaged with the rail of the window.

Referring to the parts of the device by the corresponding characters of reference

on the drawings, 1 represents the front window of the motorman's vestibule of a street car, and 2 indicates the upper cross rail of the window frame having formed transversely therethrough a slot 3 which extends slightly beyond the full width of the window sash 4. A pair of outwardly bowed brackets or supporting arms 5 having rectangular bearing heads 6 at their upper ends are mounted to embrace between the inner faces of said heads the rail 2 of the window frame from which said arms depend in opposed alignment upon opposite sides respectively of the window 1, as best shown in Fig. 2. The inner face of each of the heads 6 is provided with a central longitudinal and laterally extending rib 7 which fits freely within the slot 3 wherein it slides with the movement of said head and serves to steady and retain the arm in the vertical position in traveling therewith longitudinally of said slot. The lower end of each of the arms is formed with an inwardly turned forked extension 8 within which the folded edge of a sheet metal strip 9 is secured by screws or rivets 10 to extend in adjacent parallel relation to said arm, and secured between the folded sides of the strip 9 by rivets as at 11 is a flexible strip 12, preferably of rubber, which is adapted to bear upon and wipe the surface of the glass 13 with the movement of said arm transversely across the window. (See Figs. 2 and 3).

In order to secure the heads in opposed relation slidably engaged with the slot of the window frame, and to retain the flexible wiping strips yieldably engaged with the opposite faces, respectively, of the window glass, the outer face of each of said heads is provided with a longitudinal recess 14 having a central transverse opening 15 therethrough, and seated to bear at opposite ends within these recesses respectively are opposed arcuate leaf springs 16 having central transverse apertures 17 through which and the openings 15 of said heads a bolt 18 is extended and provided with a binding nut 19, by means of which said springs are confined under tension which is exerted upon the heads and bracket arms in a manner to yieldably retain the wiping strips slidably engaged with the window glass. The outer face of the rail 2 of the window frame may be provided with a sheet metal strip 20 se-

cured thereto at its upper edge by screws 21 and offset to overlap the head and slot 3 in the manner of an apron or guard to prevent the direct passage of air drafts therethrough.

It will now be seen from the foregoing description that the device may be adjusted to normally lie in position adjacent the vertical rail of the window sash upon either side thereof so as not to obstruct the view through the window, and that in this position the device will be conveniently accessible to the motorman or operator who may by grasping the bracket arm shift it laterally across the window, carrying the flexible strips in sliding contact with the faces of the glass in a manner to wipe and effect the removal simultaneously from both sides of the glass of any deposit of sediment or moisture that may accumulate thereon.

It will be noted that the wiping strips are preferably set to engage at their upper ends with the cross rail of the window sash so as to insure the removal of any deposit adjacent the rail which in the case of moisture would tend to flow downwardly upon the glass after the passage of the wiping strips.

I claim:

1. In a window cleaning device, the combination of a pair of opposed bracket arms each having a transverse head adapted to be slidably engaged with a slot in a window frame upon opposite sides respectively of said window, each of said arms carrying a flexible wiping strip engaging a corresponding face of the window glass, means to re-

tain said heads against angular movement in said slots, and yieldable means connecting said heads and retaining said wiping strips engaged with said glass.

2. In a window cleaning device, the combination of a pair of opposed heads each having a lateral projection adapted to be slidably engaged with a slot in a window frame upon opposite sides respectively of said window, a depending bracket arm on each of said heads carrying a flexible wiping strip engaged with the corresponding face of the window glass, a spring engaged with each of said heads, and a tie member extending through said slot and heads and engaged with said springs for exerting tension upon said heads and arms to retain said wiping strips yieldably engaged with said glass.

3. In a window cleaning device, the combination of a pair of opposed heads each having a lateral projection adapted to be slidably engaged with a slot in the upper rail of a window frame upon opposite sides respectively of said rail, a depending bracket arm on each of said heads carrying a wiping strip engaged with a face of the window glass, a depression in each of said heads and a leaf spring seated in each of said depressions, and a bolt extending through said slot, heads and springs, and confining the latter under tension to yieldably retain said wiping strips engaged with said glass.

In testimony whereof I sign this specification.

JOSEPH R. LE CLAIR.
